PREPAYMENT MECHANISM

John Prince, Hollinwood, England, assignor to
Ferranti Inc., New York, N. Y.Application December 20, 1934, Serial No. 758,498
In Great Britain December 21, 1933

8 Claims. (Cl. 194—72)

This invention relates to prepayment mechanism of the type wherein a coin-receiving member adapted to receive any of a plurality of predetermined coins of different denomination conveys motion to setting or release mechanism, which may effect movement of the "credit" section of a differential gear, means such as a motor mechanism being adapted to return the setting mechanism to a zero position which may also cause controlling means to cut off the supply of the commodity when the quantity supplied corresponding to the payment made has been expended. The invention is particularly but not exclusively applicable to prepayment electricity meters.

15 Prepayment mechanism of the type referred to above has been proposed wherein in order to set setting mechanism in accordance with the value of a coin inserted in the apparatus, a rod constituting a rotary coin receiving member is moved axially without rotation until a disc on the rod by engaging the edge of the coin causes the rod to be arrested in a position bringing the appropriate gear member thereon into mesh with a first gear member and causing the coin to move a coin chamber to unlock a further disc whereupon the rod can be rotated without axial movement to operate the setting mechanism.

The main object of the present invention is to provide improved or simplified means for effecting and controlling the movement of the rotary coin-receiving member and for conveying motion therefrom to setting or release mechanism actuated thereby.

35 Referring to the accompanying drawings:—

Figure 1 is a vertical sectional view through a form of prepayment mechanism embodying the present invention.

Figure 2 is a sectional plan thereof.

40 Figures 3, 4 and 6 are vertical cross sections of part of an electricity meter embodying said mechanism.

Figure 5 is a cross-sectional view on the line 5—5 of Figure 1.

45 Figure 7 is a front view of part of the meter with cover removed.

Figure 8 is a front elevation of the coin-receiving casing showing a form of coin support plate.

50 Figure 9 is a sectional plan of part of the arrangement of Figure 8.

Figures 10 to 18 are views of modified details, and

Fig. 19 is a perspective view of a detail of Figures 1 and 2.

In carrying the invention into effect according to one form illustrated in Figures 1 to 9 as applied by way of example to a prepayment electricity meter, I provide a slotted rotary coin-receiving member 1 mounted on bearings in a fixed casing or barrel 2, the top of which latter is furnished with a cover 3 which conveniently may be removable as shown. Slidably carried upon said rotary coin-receiving member 1 is a toothed wheel 4 which is constantly urged towards an operating handle 14 by a compression spring 37 and which is rigid with a pair of cams 5, 6, one of these cams (6) embodying three swell portions and the other (5) four such portions. In addition the toothed wheel 4 is furnished with an axial projection 7, the purpose of which is explained below.

Also slidably mounted on the rotary coin-receiving member 1 is a U-shaped member 8 urged towards an operating knob 14 by a tension spring 36 and furnished at one end with two coaxially mounted rollers 9, 10 and at the other end with a roller 11. A cylindrical cam 12 comprising a short tube in which a somewhat U-shaped notch has been cut to form a cam surface is fixed 25 with its axis perpendicular to the stationary barrel 2; this cam surface is engaged by the roller 9. A familiar similar cylindrical cam 13 but having two diametrically opposite somewhat V-shaped notches forming two cam surfaces is mounted 30 concentric with and within the said fixed cylindrical cam 12 and is rotationally rigid with the operating knob 14; the two cam surfaces are engaged by the rollers 10 and 11.

As will be seen from Figure 19 the surface of the cam 12 is level from the point marked *a* to the point marked *b*. The face of the cam then slopes downwards along the part marked 35 to a minimum position *e*.

There is then a slight rise to *d* and then a further fall to a new minimum position *e* from which it rises steeply to the level surface at point *a*. In operation the roller 9, which in the "at rest" position is in the hollow at *e*, rides up the incline from *e* to *a* so causing the U-shaped member to move longitudinally away from the operating knob. In the meantime the rollers 10 and 11 ride up the V-shaped notches formed in the cam 13 so providing a rotational movement.

When the coin-receiving member rotates 50 through 180° the roller 9 has reached the position *b* on the cam and will then travel down the slope 35 towards the barrel 2. This enables the U-shaped member to return towards the knob thus releasing the coin.

45

55

The reason for the slight rise from *c* to *d* is to prevent the apparatus from operating if the knob 14 is rotating in the reverse direction in which case the roller 9 would hit against the surfaces *d* *e* and prevent rotation.

Any one of the axially slidable cams 5, 6 or the axial projection 7 is adapted selectively according to the diameter of the coin inserted to be brought into alignment with a tappet rod 15 connected to setting mechanism so that actuation of this latter mechanism may be effected in correspondence with the value of the coin.

Mounted rigidly upon the rotary coin-receiving member 1 is a cam 16 engaging a further tappet 17 by means of which the closing of a switch 18 may be effected and associated with this cam 16 is a pawl 19 engaging a ratchet wheel 19a fixed to the stationary barrel 2; the ratchet wheel 19a being partly cut away at its periphery over an arc corresponding to a movement of the pawl from its zero position through about 90° in order to enable partial reversal of the rotary coin-receiving member 1 in circumstances explained below.

Pivotedly mounted upon the rotary coin-receiving member 1 is a spring-urged curved flap 20 (Figures 1 and 2); this flap serving to support the coin after its insertion. In Figures 8 and 9 the arrangement of curved flap is shown, such flap 20 being mounted upon a spindle 21 rotated under the urge of a release arm 22 mounted rigidly upon a further spindle 23 passing to the exterior of the stationary barrel cover. The exterior portion 24 of this further spindle 23 is formed in the shape of a "screw head" and is sunk flush with the casing. The head is provided with a slot as shown of sufficient width to enable the edge of any particular coin to be inserted in order to rotate it.

Rotation of this further spindle 23 causes the arm 22 to bear against the spring-urged curved flap 20, which latter rocks about its pivot 21 to permit the coin to drop. By arranging the "screw head" as described, it cannot be accidentally rotated so avoiding dropping wanted coins.

The cover 3 of the stationary coin barrel 2 carries a slotted spindle 25, the slot 26 in which is capable of registering with a slot 27 in the cover or the spindle 25 is capable of closing said slot, and rigid with this spindle is a member embodying a series of normally shaped toothed wheel elements 28, 29 and 30, the number of such elements being equal to the number of coins capable of actuating the apparatus, there being not less than two such elements. This series of elements is associated with a further series of single toothed locking pinions 31, 32, 33 and 34, the number of these pinions being one more than the number of normally shaped toothed wheel elements. The normally shaped toothed wheel elements 28, 29, 30 are adapted to engage the toothed wheel 4 which is axially slidable on the rotary coin-receiving member 1, and the arrangement is such that the said axially slidable toothed wheel 4 can only be moved axially when the locking pinions are in such angular position that their single teeth are capable of meshing with teeth on the wheel 4.

The tappet rod 15 is connected to a slidable rack 55 engaging a pinion 56 carrying a pawl (not shown) which in turn engages a ratchet wheel (not shown) communicating motion to the "credit" member 59 of a differential gear, "coins unused" indicator dials 60 and a "money inserted" indicating device 61. In connection with the said indicator and counting device I provide suitable means, such as a spring-urged roller wheel 62

engaging a notched disc 63, for eliminating the effect of backlash.

In operation, upon insertion of a coin, say a penny, through the slot 27 in the cover 3 it passes through the slot 26 in the slotted spindle 25 and is introduced in the slot of member 1 and between the toothed wheel 4 and the U-shaped member 8.

As the knob 14 is rotated the cylindrical cam 13 rigid therewith drive the rollers 10 and 11 thereby thrusting the roller 9 of the U-shaped member against the fixed cam 12; this latter is so shaped that the rotary movement of the knob is converted into an axial movement of the U-shaped member with which is combined a slight rotational movement the resulting movement of the U-shaped member being thus helical. This latter movement owing to the meshing of the wheel 4 with the locking pinion 34 slightly rotates the spindle 25 to effect closure of the coin slot. The U-shaped member bears against the edge of the coin and thus in turn moves axially the toothed wheel 4 and movable cams 5, 6 and axial extension 7 rigid therewith until a position is reached in which the axial extension 7 on the toothed 25 wheel comes into register with the first-mentioned tappet rod. The toothed wheel is also now in register with the normally shaped toothed wheel element 28 and continued rotation of the knob 14 now effects pure rotation of the rotary coin- receiving member 1, and also allows the roller 9 to run along the incline 35 on the fixed cam 12 and so permit the U-shaped member 8 to move axially towards the knob 14 sufficiently to enable the penny to fall into the coin container. Immediately after this takes place the rotary member 1 will have reached a position such that the axially movable toothed wheel becomes freed and can therefore move axially under the influence of its spring 37 into the position it originally occupied before insertion of the coin.

A similar action takes place upon insertion of either a sixpence or a shilling except that the corresponding cam 5 or 6 is brought into engagement with the tappet rod 15 and the latter is 45 thrust forward three or four times according to the number of swell portions on the corresponding cams so that the total displacement of the tappet rod is proportional to the value of the coin inserted.

Unless a coin of predetermined denomination and intact in diameter be inserted the axially movable toothed wheel will not be brought into engagement with one of the normally shaped toothed elements in the casing cover and consequently rotation of the toothed wheel (except for an initial movement) will be impossible. Should a coin of incorrect diameter be inserted and operation of the knob 14 be attempted the toothed wheel 4 will be thrust insufficiently far or too far (according to whether the coin is of deficient or excessive diameter) to engage the corresponding normally shaped toothed wheel element but will engage instead one of the locking pinions which will permit a small degree of rotation only. 65 The arrangement is such, however, that sufficient reverse rotation of the knob is permitted, due to the smooth part of the fixed ratchet 19a in the stationary casing, to enable the said coin to be allowed to drop into the coin receptacle upon 70 actuation of the curved flap 20 by operation of the head 24.

Instead of providing a detachable cover for the coin-receiving chamber, the cover may be formed in one therewith as is indicated in Figure 10.

Means for closure of the slot 27 after insertion of a coin additional to the closure effected by the spindle 25 may be employed such as are illustrated in Figures 11 and 12 according to which 5 a flap 38 hinged at 39 to a bearing member 40 is provided and a member 41 is furnished on the coin-receiving member 1, the arrangement being such that except in the zero position, as indicated in Figure 11, the flap 38 is lifted as in 10 Figure 12 to close the coin slot.

As an alternative to providing a pair of cams and a projection for operating the setting tappet 15, cams 5, 6 and 42 alone may be employed as indicated in Figure 13 or projections 43, 44, 45, 15 Figures 14 and 15.

In the latter arrangement the projections are alternatively brought into engagement with one end of a lever 46 pivoted at 47, this lever being in turn connected to a tappet rod 15 by means of 20 a pin 48 and slot 49.

When cams are employed these may either be furnished with two or more swell portions as in Figure 6 whereby the total forward movement imparted to the tappet 15 is made up of more 25 than one component imparted thereto during one revolution of the operating knob or with cams having single swell portions, as indicated in Figure 18.

In order to prevent the possibility of rotating 30 the coin-receiving member through more than one revolution for any individual coin inserted a locking device may be provided of which a convenient form is illustrated in Figures 16 and 17.

In these figures a sliding carriage 50 is mounted 35 on one side of the fixed casing or barrel 2 and is urged by means of a tension spring 51 to move longitudinally in a direction away from the operating knob 14 and to rest against a face of the member 4.

The carriage is furnished with two abutments 40 52, 53 which are adapted to co-operate with a projecting arm 54 rigidly mounted on the coin-receiving member 1.

Before a coin is inserted the abutment 52 lies 45 in the path of the projecting arm but when a coin is inserted and the projecting arm rotated the abutment 52 by a slight movement in the same direction as that of the toothed member 4 moves out of the path of the projecting arm and enables the latter to perform one rotation. If 50 at the end of this rotation the member 4 has not been released so as to return to its zero position, the abutment 53 will stand in the path of the projecting arm and thus prevent further rotation of the coin-receiving member but if as 55 normally occurs the member 4 correctly returns to its zero position, then the carriage is moved back to its initial position in which the abutment 52 co-operates with the projecting arm.

I claim:

1. Prepayment mechanism comprising a carrier member, bearings restricting movement thereof to rotation about a fixed axis, a member axially slidable on but rotationally rigid with said carrier member, a further member axially slidable on but rotationally rigid with said carrier member, manual operating means, bearings restricting movement thereof to pure rotation, motion resolving means between said manual operating means and said first named axially slidable member imparting both rotational and axial movement components to said first named axially slidable member and thence by way of a coin inserted between said axially slidable members 15 imparting an axial movement component to said further axially slidable member, setting mechanism and a plurality of means rigid with said further axially slidable member individually actuating said setting mechanism. 20

2. Prepayment mechanism as claimed in claim 1 wherein at least one of said means rigid with the further axially slidable member comprises a cam.

3. Prepayment mechanism as claimed in claim 25 1 wherein at least one of said means rigid with the further axially slidable member comprises a projection which coacts with a lever.

4. Prepayment mechanism as claimed in claim 30 1 wherein said further axially slidable member comprises a toothed wheel co-operating with any of a plurality of normally shaped toothed elements and any of a plurality of single toothed locking pinions rigidly mounted on a slotted spindle. 35

5. Prepayment mechanism as claimed in claim 35 1 including slot closing means comprising a slotted rotatable rod rigid with a plurality of normally shaped toothed wheel elements and with a plurality of single toothed locking elements, 40 one of said elements being always in mesh with teeth on said further axially slidable member.

6. Prepayment mechanism as claimed in claim 45 1 including a pawl associated with said carrier and a fixed ratchet wheel, part of the periphery of which is toothless, co-operating with said pawl.

7. Prepayment mechanism as claimed in claim 50 1 wherein said motion resolving means comprises a cylindrical cam.

8. Prepayment mechanism as claimed in claim 55 1 including automatic motion arresting means associated with said carrier member serving to prevent more than one rotation of the carrier member with any individual inserted coin.

JOHN PRINCE.
